Primary Examiner — T Chase Nelson(74) *Attorney, Agent, or Firm* — Pate Baird, PLLC(57) **CLAIM**

The ornamental design for a sole for footwear, as shown and described.

DESCRIPTION

The sole FIGURE is a bottom plan view of a sole for footwear showing my new design.

The broken lines depict portions of an upper of footwear corresponding to a sole for footwear that form no part of the claimed design, as well as environmental structure in the form of a shoe upper, which also forms no part of the claimed design.

1 Claim, 1 Drawing Sheet(56)
